INDUSTRIAL GAUGING HEAD FOR DETECTING MATERIAL PROPERTIES

John H. Schlaechter, Columbus, Ohio, assignor to The
Industrial Nucleonics Corporation, a corporation of
Ohio

Filed Nov. 6, 1961, Ser. No. 67,381

Term of patent 14 years

(Cl. D52—6)

Fig. 1

Fig. 2

Fig. 3

FIG. 1 is a perspective view of an industrial gauging head for detecting material properties showing my new design;

FIG. 2 is a side elevation thereof on a reduced scale; and

FIG. 3 is another side elevation on a reduced scale.

I claim:

The ornamental design for an industrial gauging head for detecting material properties, as shown.
